(57) **CLAIM**

The ornamental design for a universal tank lever, as shown and described.

DESCRIPTION

FIG. 1 is a top front perspective view;

FIG. 2 is a top plan view;

FIG. 3 is a front elevation view;

FIG. 4 is a bottom plan view;

FIG. 5 is a left end view;

FIG. 6 is a right end view; and,

FIG. 7 is a rear elevation view.

The broken line showing portions of the lever is included for the purpose of illustrating a portion of the lever that forms no part of the claimed design.
